UNITED STATES PATENT OFFICE.

CHARLES L. BETTS, OF NEW YORK, N. Y., ASSIGNOR TO R. E. DIETZ COMPANY, OF NEW YORK, N. Y.

DESIGN FOR A LAMP.

41,267.

Specification for Design.

Patented Mar. 28, 1911.

Application filed January 21, 1910. Serial No. 539,436. Term of patent 14 years.

To all whom it may concern:

Be it known that I, CHARLES L. BETTS, a citizen of the United States, residing at New York, borough of Brooklyn, in the county of Kings and State of New York, have invented a new, original, and ornamental Design for a Lamp, of which the following is a specification.

In the accompanying drawing: Figure 1 is a perspective rear view of an electric tail lamp for automobiles and other vehicles embodying this design. Fig. 2 is a perspective side view of the lamp.

Like reference characters refer to like parts in both figures.

The design comprises as its main features an approximately globular or spheroidal body A, somewhat elongated longitudinally,

a rear portion B which forms the face of the body and which has approximately the form of a spherical segment, an annular molding C arranged at the junction of this spherical rear portion B with the spheroidal body A, and convex protuberances D having approximately the form of spherical segments and arranged at the sides of the spheroidal body, the surface of the latter being plain at the top between these protuberances.

I claim as my invention:

The ornamental design for a lamp, substantially as shown and described.

CHARLES L. BETTS.

In the presence of—

E. D. PRICE,

FRED H. TWOMBLY.

Copies of this design may be obtained for five cents each, by addressing the "Commissioner of Patents, Washington, D. C."
